(57) **CLAIM**

The ornamental design for an insert for a drill measurement system, as shown and described.

DESCRIPTION

FIG. 1 is a perspective view of an insert for a drill measurement system;

FIG. 2 is a front view of the insert for a drill measurement system of FIG. 1;

FIG. 3 is a rear view of the insert for a drill measurement system of FIG. 1;

FIG. 4 is a left side view of the insert for a drill measurement system of FIG. 1;

FIG. 5 is a right side view of the insert for a drill measurement system of FIG. 1;

FIG. 6 is a top view of the insert for a drill measurement system of FIG. 1; and,

FIG. 7 is a bottom view of the insert for a drill measurement system of FIG. 1.

The broken lines in the drawing indicate environmental structure and form no part of the design to be patented.

1 Claim, 4 Drawing Sheets
